UNITED STATES PATENT OFFICE.

JOHN J. BOERICKE, OF MERION, PENNSYLVANIA.

METHOD OF PRODUCING METALS.

1,277,034.

Specification of Letters Patent. Patented Aug. 27, 1918.

Application filed July 20, 1914, Serial No. 251,335. Renewed June 29, 1918. Serial No. 212,664.

To all whom it may concern:

Be it known that I, JOHN J. BOERICKE, a citizen of the United States, residing at Merion, in the county of Montgomery and State of Pennsylvania, have invented certain new and useful Improvements in Methods of Producing Metals, of which the following is a specification.

This invention has reference to the reduction of metals and their alloys from ores and oxides or other metallic compounds by what is known as the exothermic process. The primary object of this invention is the provision of a novel method of instituting and carrying out the exothermic reaction with a view of obtaining a superior product economically and with rapidity. In the accompanying drawing I have shown in diagrammatic form apparatus which illustrates certain steps of my improved method, the figure being a sectional view of the crucible or container in which the reduction takes place.

In brief, the alumino-thermic process to which this invention relates consists in reducing ores and metallic compounds by mixing with the ores aluminum, an alloy thereof, or some other agent having a strong affinity for oxygen, and then in instituting a reaction by the ignition of a portion of the mass. In carrying out my improved method, I take a relatively small quantity of the ore to be reduced and mix with it a reducing agent, such as aluminum preferably in flaked form, and I then place the mixture in a crucible or container 7 such as shown in the drawing. I prefer to preheat the materials and also the crucible and this step, while not essential, has been found to materially improve the quality of the product produced.

The next step of the process is the institution of the exothermic reaction, and this is done either by directly igniting a portion of the mixture in the crucible or by the use of a fuse or the like. After this institution of the reaction, I feed into the crucible as fast as may be required, a mixture of the ore and aluminum which I prefer to store in a hopper or receptacle 8 which is provided with a discharge spout 9 controlled by suitable valve mechanism 10. The mixture contained in the hopper may be the same as that already described, but I have found that superior results are obtained by

using the aluminum reducing agent in the form of ingots.

I am aware that it is well known in this art to use powdered aluminum as a reducing agent, and that exothermic processes *per se* 60 are old. However, in carrying out the process heretofore known, the crucibles or containers have been practically filled with a mixture of the compound and the powdered aluminum, and the endothermic reaction has 65 been instituted on the surface of the mixture and spreads downwardly through the mass. By my process, however, only a small quantity of the mixture is placed in the crucible and a reaction instituted, after 70 which the material to be reduced is fed into the crucible so that the reaction spreads from beneath upward, the quantity of the material which is fed into the crucible being regulated in order to add just the right proportion of new material to the incandescent mass.

I have found that the foregoing method has enabled me to produce a superior and more uniform grade of product, and this 80 from comparatively low grade ores. It will be apparent that it is far more advantageous to ignite a small portion of the mixture and then feed thereto additional quantities, the amount of which can be fully controlled by the operator. Among the particular advantages of the method are that the ores can be reduced in far larger quantities at a time, and with greater rapidity, and at the same time the quality of the product obtained is greatly improved and a uniformity in product obtained throughout a number of successive operations, the importance of which will be readily seen where it is necessary to produce a large quantity of a given 95 metal containing certain specified percentages of the various constituents. In securing the foregoing results and advantages, the feeding of the material to be reduced under control has an important bearing as 100 operative conditions vary considerably, and by my method an experienced operator can successfully meet such changes in condition with uniform results.

Another advantage of my improved process is that, because of the manner in which the reaction is carried out, a greater quantity of the mixture is subjected to the action of the atmosphere, the result of which is that more oxygen is supplied and the impurities 110

are burnt up. In connection with this feature, I prefer to use a wide crucible, that is, one having considerable cross sectional area, as opposed to the narrow and deep crucibles, so that the reaction is extended over a greater area, thereby exposing the mass to the action of the atmosphere, and eliminating the impurities which otherwise would remain in the product.

10 I claim:-

1. The herein described process of reducing metallic compounds which consists in igniting a mixture of the compound to be reduced and aluminum and then in feeding to the ignited material a mixture of the compound and aluminum under control so that the reaction is instituted from beneath upward.

2. The herein described steps in the exothermic process of reducing metallic compounds which consist in placing a relatively small quantity of a mixture of the compound to be reduced and aluminum in a crucible, in instituting an exothermic reaction in such mixture and in feeding into the crucible a mixture of the compound to be reduced and aluminum.

3. The herein described steps in the exothermic process of reducing metallic compounds which consist in placing a relatively

small quantity of a mixture of the compound to be reduced and a reducing agent in a crucible, in instituting an exothermic reaction in such mixture and in feeding thereto under control a mixture of the compound to be reduced and a reducing agent.

4. The herein described process of reducing metallic compounds which consists in mixing the compound with flaked aluminum, in instituting an exothermic reaction in such mixture and in adding thereto quantities of a mixture of the compound and ingot aluminum.

5. The herein described process of reducing metallic compounds which consists in igniting a mixture of the compound and a reducing agent in a crucible having a relatively extended area so that the greater portion of the mixture in which the reaction is taking place is exposed to the action of the atmosphere, and then in feeding to the ignited material a mixture of the compound and a reducing agent.

In testimony whereof I have hereunto signed my name in the presence of the two subscribed witnesses.

JOHN J. BOERICKE.
